UNITED STATES PATENT OFFICE.

HERMAN C. EGGERT, OF INDIANAPOLIS, INDIANA.

PROCESS IN THE MANUFACTURE OF METAL SIGNS, TABLETS, ETC.

Application filed February 12, 1923. Serial No. 618,726.

To all whom it may concern:

Be it known that I, HERMAN C. EGGERT, a citizen of the United States, and resident of Indianapolis, Marion County, Indiana, have invented certain new and useful Improvements in Processes in the Manufacture of Metal Signs, Tablets, Etc., of which the following is a specification.

This invention relates to a process in the manufacture of metal signs, tablets, and the like, wherein an etched background effect may be given to the final product.

Furthermore, the type from which the sign matter is to be prepared, are assembled in a manner known as the offset pastel, except that for the purpose of the present invention, the assembling arrangement is directly the reverse of that in such system.

In carrying out the present method, the form is made up, as in the ordinary chase used in a printing process, and the type assembled in a manner known as the offset pastel, except that for the purpose of this invention, the nick of the type are set down instead of up as in the offset pastel process. After the form is completed, a wax impression is made thereof, but prior to impressing the wax matrix onto the form, the impression of a sanded surface, as an ordinary piece of sand paper, is made on the wax matrix. The matrix with the sand paper impression is then ready to receive an impression from the form, and this impression is made so as to carry the characters and letters thereof into the matrix at a greater depth than that of the sanded impression surface.

Following the formation of the matrix, the final product is formed by the well known electrotyping process, which need not be specifically described herein.

For convenience in understanding the process, the invention is illustrated in the accompanying drawings, in which:

Fig. 1 is a view of a chase with the type arranged therein.

Fig. 2 is a plan view of the matrix following the application of the sand paper impression thereto.

Fig. 3 is a view of the final product.

The type 1 are arranged in a chase 2 in accordance with the manner described in the offset pastel process, except that the type are reversed, that is, the nick is down. A

sanded body, as for example a piece of sand paper, not shown, is impressed upon the wax matrix 3 leaving the roughened or etched appearance of such surface indicated at 4. The form is then pressed into the matrix to a depth below that of the sand paper impression and following the electrotyping process and suitable backing, the product indicated at 5 is secured. This product, it will be noted, has the letters raised from the surface, or in relief, and these letters have smooth surfaces, while the remaining portions of the sign or tablet have the appearance of being etched. Of course any portion or portions of the tablet may be given this etched appearance simply by the appropriate sand paper design, though it is preferred that the entire surface not occupied by the letters or characters be given the etched appearance.

The characteristic feature of the invention is the provision of this etched appearance in the final product resulting from an electrotyping process by the use of sand paper or a sanded body, which is initially impressed into the matrix prior to the impression of the form therein.

Claims:

1. The method herein described of forming metal signs and tablets by the electrotyping process with a surface imitation of etching, consisting in preparing the form and matrix, impressing a sanded body into the matrix, and then impressing the form in the matrix, and producing the final product by electrotyping from said matrix.

2. The method herein described of forming metal signs and tablets by the electrotyping process with a surface imitation of etching, consisting in preparing the form and matrix, impressing a sanded body into the matrix, and then impressing the form in the matrix to a depth to eliminate the sand body impressions from the form outlines, and producing the final product by electrotyping from said matrix.

In witness whereof, I hereunto subscribe my name to this specification in the presence of two witnesses.

HERMAN C. EGGERT.

Witnesses:

CHAS. A. SHERWOOD,
JOHN E. MILLER.
